INVENTOR:

Theodore W. Foster

UNITED STATES PATENT OFFICE.

THEODORE W. FOSTER, OF PROVIDENCE, RHODE ISLAND.

DESIGN FOR A BREASTPIN.

SPECIFICATION forming part of Design No. 15,533, dated November 11, 1884.

Application filed July 31, 1884. Term of patent 7 years.

To all whom it may concern:

Be it known that I, THEODORE W. FOSTER, a citizen of the United States, residing at Providence, in the State of Rhode Island, have invented and produced a new and original Design for the Front Plate of a Jewelry Pin, of which the following is a specification, reference being had to the accompanying drawings, forming a part thereof.

10 Figure 1 is a front view of my newly-designed jewelry pin. Fig. 2 is an edge elevation of the same. Fig. 3 is a transverse section taken in the line $\alpha\alpha$ of Fig. 1.

The leading feature of my design consists in 15 a plate the outline and front surface of which represent a table-knife, with the outline edge of the blade portion turned backward from its front and having an ornamented handle.

In the accompanying drawings, A is the front plate of a jewelry pin in the form of a table-knife, the blade b of which has a backwardly-turned boundary edge, c , and the handle a in raised form, also having an ornamented surface. 20

I claim—

The design for a jewelry pin herein shown 25 and described, the same consisting of a plate having the shape of a table-knife, with the outline edge of the blade portion turned backward from the front, and the surface of the handle ornamented, as set forth.

THEODORE W. FOSTER.
